[57] **CLAIM**

The ornamental design for a fingernail protector for a
typewriter key, as shown and described.

DESCRIPTION

FIG. 1 is a perspective view of the fingernail protector
for a type-writer key embodying the design;

FIG. 2 is a elevational view thereof, all elevational
views being identical to the front end shown in FIG. 2;

FIG. 3 is a top plan view thereof; and,

FIG. 4 is a bottom view thereof.

FIG.1.

FIG. 2.

FIG. 3.

FIG. 4.
